UNITED STATES PATENT OFFICE

2,090,027

OIL BURNER

Walter R. Brown, Pontiac, Mich., assignor of
 fifty-one per cent to Marshall E. Smith and
 Corliss Armstrong, both of Pontiac, Mich.

Application October 5, 1936, Serial No. 104,114

9 Claims. (Cl. 158—28)

The invention relates to providing oil burners of the wick type with an automatic lighter, and has as one of its principal objects the provision of a pilot light effective upon initial movement of the wick to its operating position to ignite the wick, and is adapted to be extinguished upon further upward movement of the wick during the operation of the burner.

A further object of this invention is to provide a novel construction of pilot light adapted to be re-ignited by the main wick upon movement of the latter to its inoperative position.

Still further it is an object of this invention to provide a device which will possess a minimum number of parts and which will therefore be capable of economical manufacture and assembly and which will materially cut down the time and annoyance involved in lighting oil burners of this type.

With the foregoing as well as other objects in view, the invention resides in the novel details of construction and operation illustrated and about to be described.

In the drawing:

Fig. 1 is a longitudinal sectional view through an oil burner constructed in accordance with this invention;

Fig. 2 is a cross sectional view taken substantially on the plane of the line 2—2 of Fig. 1;

Fig. 3 is a sectional view through the automatic lighter unit taken substantially along the line 3—3 of Fig. 2.

Referring now to the drawing more in detail, it will be noted that there is illustrated in Fig. 1 an oil burner 10 comprising an annular casing 11 and a wick tube 12 concentrically arranged within the casing 11 and having a diameter less than the diameter of the casing 11 to provide space for receiving a wick 13 and suitable actuating means 14 supported on the outer wall 15 of the casing 11 to operate the wick.

Secured to the inner portion of the burner 10 is an apertured plate 16 adapted to support a flame spreader designated generally by the reference character 17.

It will be noted that in Fig. 1 the casing 11 is provided approximately midway between its upper and lower extremities with a return bent portion 18 forming a shoulder for a flue 19 of conventional design.

Firmly secured to the casing 11 at one side thereof is a lighter unit 20 consisting of a fuel chamber 21, a pilot wick tube 22 and a wick 23. The pilot wick 23 extends from the fuel chamber 21 through the pilot wick tube 22 beyond a slot 24

in the top portion of the annular casing 11. This pilot wick tube consists of an outer portion of the wall 15 and an upper portion 25 of the automatic lighter unit 20. This upper portion 25 runs substantially parallel to the wall 15 of the casing 11 from the fuel chamber 21 to the slot 24 in the top of the casing. At this point the upper portion 25 extends inwardly to conform substantially to the contour of the top portion of the casing 11.

A pilot wick adjuster 26 is incorporated in the automatic lighter unit 20 to allow for adjustment and replacement of the pilot wick 23. This may be of any of the known general types for adjusting wicks, but in my preferred form it consists of an adjuster rod 27 upon which are mounted two wick engaging gears 28 and 29. The rear portion of the rod 27 is seated in the mounting 30 and the front portion is seated in the mounting 31. A packing nut 32 is preferably mounted on the rod 27 upon the outer side of the fuel chamber 21 to prevent leakage of the fuel. A hand wheel 33 is attached to the outer end of the rod 27. Fuel is supplied to the fuel chamber 34 of the burner 10 through an opening 35 connected to suitable pipe means 36. The fuel supply for the lighter unit 20 is derived from the fuel chamber 34 of the main burner by means of holes 37 and 38 in the side wall of the casing 11, leading directly from the fuel chamber 34 of the burner 10 into the fuel chamber 21 of the automatic lighter unit. These holes are preferably placed at different levels to allow the escape of air and to guard against possible blockage of one of the holes.

The operation of the automatic lighter unit is as follows: The pilot wick 23 is turned up by the adjuster 26 to a position approximately flush with the top of the casing 11. It is lighted and then adjusted to give the smallest possible flame. When the main wick 13 of the burner 10 is desired to be lighted, it is moved up by mechanism 14 so that the top of the wick contacts the flame from the pilot 23 and thus ignites the main wick 13. Further upward movement of the main wick 13 will snuff the pilot by forcing the ignited portion of the wick 23 against the inwardly extending portion of the outer wall 25 of the lighter unit 20. When the burner 10 is to be shut off, the main wick 13 is slowly lowered by mechanism 14 and before it is extinguished by the lack of air in the wick tube 12, it frees the pressure upon the pilot wick 23 and allows it to ignite from the main wick 13.

What I claim as my invention is:

1. In a liquid fuel burner having a wick sup-

- ported for movement therein, a pilot light predeterminedly positioned with respect to the wick to ignite the latter upon initial upward movement of the wick and extinguishable upon continued 5 upward movement of the wick.
2. In a liquid fuel burner having a wick supported for movement therein, an adjustable pilot light predeterminedly positioned with respect to the wick to ignite the latter upon initial upward 10 movement of the wick and extinguishable by the continued upward movement of the wick.
3. In a liquid fuel burner having a wick supported for movement therein, a pilot light predeterminedly positioned with respect to the wick 15 to ignite the latter upon initial upward movement of the wick and extinguishable upon continued upward movement of the wick, said pilot light being ignited upon the downward movement of the wick.
- 20 4. In a liquid fuel burner having a movable wick, a pilot light predeterminedly positioned with respect to the wick to be ignited upon the downward movement of the burning wick.
5. In a liquid type fuel burner having a casing 25 and a wick supported for movement within the casing, a pilot light predeterminedly positioned with respect to the wick to be extinguished during operation of the wick and re-ignited upon downward movement of the wick.
- 30 6. In a liquid fuel burner having a casing and a movable wick within the casing, an igniting unit attached to the casing, means for supplying fuel to the unit, a pilot wick carried by the unit predeterminedly positioned with respect to the wick to ignitably engage the wick upon initial upward movement of the wick, and extinguishable upon continued upward movement of the wick.
7. In a liquid type fuel burner having a casing and a movable wick, an igniting unit attached to the casing, a pilot wick carried by the unit, said pilot wick being predeterminedly positioned with respect to the wick to be extinguished during operation of the wick and to be ignited by the wick upon its downward movement.
8. In a liquid type fuel burner having a casing, a slot in the casing, a main fuel chamber, wick tube and a wick adjustably mounted within the tube, an igniting unit attached to an outer portion of the casing, a fuel chamber in the unit fed by the main fuel chamber, a pilot wick extending from the fuel chamber to the top inner portion of the casing and positioned to lightably engage the main wick upon initial upward movement of said wick, and extinguishable upon continued upward movement of the wick.
9. In a liquid type fuel burner having a casing and a main burner wick supported for movement within the casing, an igniting unit attached to the casing and having a pilot wick predeterminedly positioned with respect to the main burner wick to be extinguished by the main burner wick upon movement of the latter from the casing, and re-ignited by the main wick upon movement of the latter toward the casing.

WALTER R. BROWN.
